BOARD MACHINE

William H. Sutherland, York, and Charles L. Ellis, Bradford Hills, Pa.; said Ellis assignor to Downingtown Manufacturing Company, Downingtown, Pa., a corporation of Pennsylvania

Application September 29, 1931, Serial No. 565,898

27 Claims. (Cl. 92—42)

This invention relates to cylinder type paper-making machines and has for an important object thereof the improvement of the present method of forming a sheet so that the speed of formation may be increased and waste resulting from imperfect products reduced.

In the cylinder type paper-making machine the forming or wet end of the machine consists of one or more vats each containing a cylinder 5 mold against which operates a couch roll and having associated therewith a felt passing between the cylinder mold and the couch roll.

In operation, the vat or vats receive a constant supply of paper-making fibres in extremely dilute 15 form, the percentage of fibre present in the water often being as low as .25%. As the cylinder molds revolve the water in the vats passes through the wire mesh of the molds and the paper fibres cling to the surface of the mold until brought 20 into contact with the felt to which they cling. At this time the fibres are in the form of a very wet web of paper and from the cylinder molds the web is carried through the press, drying, and finishing sections of the machine.

It has been found that upon an increase in the speed of a machine of this character a greater 25 percentage of water is carried along with the felt and the paper web with the result that this water forms in drops or globules on the under side of the sheet disarranging the fibres and causing the sheet to "crush" at the couches or at the press rolls.

A further object of the present invention is the provision of a structure rendering it possible to deliver the web of paper as it passes from cylinder mold to cylinder mold with a lower water content than is possible with the standard apparatus and to operate the machine at a greater speed 35 than is now possible while reducing the liability to "crush" at the couches or presses and providing a more homogeneous and uniform sheet than is ordinarily produced.

A further object of the invention is the improvement of the construction shown in our 45 prior application, Serial No. 421,476, filed January 17, 1930, for Multicylinder board machine, of which application this application is in part a continuation.

A further and more specific object of the 50 invention is the extension of the construction illustrated in said prior application insofar as the use of the extractor roll mechanism is concerned to enable operation of multi-cylinder board machines without the use of primary presses while

at the same time producing paper of a better quality at least the same speed at which the machine ordinary operates.

These and other objects we attain by the construction shown in the accompanying drawings wherein, for the purpose of illustration, we have shown a preferred embodiment of our invention and wherein:

Fig. 1 is a side elevation of a cylinder machine constructed in accordance with our invention; 10

Fig. 2 is a similar view of a slightly modified form of the cylinder machine;

Fig. 3 is a vertical sectional view through a type of suction roll suitable for use as a drum roll or auxiliary couch roll; 15

Fig. 4 is a fragmentary perspective showing the construction of the extractor roll;

Fig. 5 is a semi-diagrammatic view illustrating one arrangement permitting elimination of primary presses; 20

Fig. 6 is a modification of the arrangement shown in Fig. 5;

Fig. 7 is a further modification of the arrangement of Fig. 5; and

Fig. 8 shows a still further modification of 25 the arrangement shown in Fig. 5.

Referring now more particularly to the drawings, the numeral 10 generally designates vats which may be of any usual or ordinary construction, 11 cylinder molds operating in the vats and 30 driven in the usual manner, 12 couch rolls cooperating with the cylinder molds, and 13 the felt web passing between the couch and cylinder rolls and about a drum roll disposed at the discharge of the wet end of the machine. 35

In accordance with our invention, we provide an extractor roll 15 having pressure engagement with a cooperating press roll "P" which may comprise the drum roll hereinbefore referred to. This extractor roll is constructed similarly to 40 the construction of a cylinder mold but is more heavily constructed, the surface thereof comprising a curved and heavily reinforced perforated wire cloth through which water may readily pass. This extractor roll may operate in a vat 17 45 which may or may not contain water in which the roll operates. A shower pipe 18 is arranged at the rear of the roll to direct water against the roll after the engagement of the roll with the web so that any fibres which may cling 50 to the extractor roll will be washed therefrom. At the opposite side an air pipe 19 is disposed for directing air against the cover 16 of the roll to blow from the openings thereof any water which may tend to cling therein before the

surface of this roll again comes in contact with the web. One of the press roll "P" and extractor roll 15 is equipped with counter-weighted lever mechanism generally designated at 20 so that a 5 desired and relatively heavy pressure engagement between the rolls may be maintained. This arrangement of the extractor roll in combination with the press roll may be used with cylinder machines having one or more vats.

10 Where the machine contains more than one vat, auxiliary couch or press rolls 21 can be disposed between the vats and have associated therewith further extractor rolls 15-a similar to the extractor roll just described and equipped with 15 spray and air pipes 18-a and 19-a as shown in Figs. 2 and 6. The use of auxiliary couch rolls and associated extractor rolls in this manner is preferably resorted to where it is desired that the speed of operation of the machine be increased 20 as under these circumstances more water is carried over on the under side of the sheet and the intermediate extractor rolls serve to eliminate this extra water. The pressure contact mechanism between the auxiliary couch rolls 21 and auxiliary 25 extractor rolls 15-a similar to that employed in the roll "P" and its associated extractor may be provided as generally designated at 28-a.

In Fig. 2 we have illustrated a modification of the structure wherein top press roll of the extractor is a suction roll 22 (Fig. 3). The suction roll 30 will, of course, augment the action of the extractor and pressure rolls to increase the extraction of water from the sheet. Any well known type of suction roll may be employed for this purpose. Such suction rolls, as is well known to those 35 familiar with the art, comprise an outer rotating perforated shell 23 having an interiorly disposed suction box 24 for producing suction through the shell at a desired point. The auxiliary couch rolls hereinbefore referred to may likewise be constructed as suction rolls.

In Figs. 5 to 8 inclusive, we have illustrated extensions of the above arrangement to eliminate the use of top felts and primary presses in multi-cylinder paper machines. In Fig. 5 the felt 18 45 instead of being returned over the machine and joined with a second or upper felt is passed directly over a plurality of extractor presses each including the extractor roll 15 and the co-operating press roll "P", and passed directly through the first press of what constitutes the normal 50 press end of the machine minus the usual primary presses; in other words, this felt is passed directly to the first main press of the machine and returned over the top roll of this press to the cylinder molds. It has been found that by the 55 use of a plurality of these extractor presses the sheet is sufficiently dried to enable its passage through the main press without crushing so that the extractor presses perform the same function as the primary presses ordinarily employed. Due to the fact that the construction of the extractor 60 presses permits the sheet to be directly engaged with the extractor roll it is unnecessary that the felt 18 be joined by second felt as when the primary presses are employed. Since the extractor 65 presses are more readily driven than the primary presses, requiring less power, the cost of operation of the machine is reduced without giving consideration to the complete elimination of the top felt which in many machines costs as much as fifteen thousand dollars a year for replacement.

In Fig. 6 the structure of Fig. 5 has been modified to include the auxiliary extractor rolls and

co-operating couch rolls 15-a and 21 disposed between certain of the cylinder molds 11.

The arrangement of Fig. 7 is identical with that of Fig. 5 with the exception of the fact that the extractor presses are disposed at the opposite end of the cylinder molds from the first press and the felt with the sheet thereon is returned over the cylinder molds for engagement with the first press. In an arrangement of this character the felt will, of course, pass about the lower press roll 10 in order that it may be properly positioned for return to the cylinder molds.

In the form shown in Fig. 8, we have illustrated an arrangement permitting the reduction of the number of extractor presses employed in the 15 machine. This is accomplished by substituting for the usual first main press a suction press "S. P." in which the felt-engaging roll 22-a is a suction roll.

As will be obvious from the foregoing, the arrangement of the machine is capable of a considerable modification in adapting it to uses with various types of cylinder paper machines, and to use at various speeds, we accordingly do not limit ourselves to the specific structure hereinbefore set forth except as hereinafter claimed.

We claim:

1. In a cylinder paper machine, the combination with a cylinder vat unit including a vat, a cylinder mold rotating therein, a couch roll co-acting with the cylinder mold, a carrier passing between the couch roll and cylinder mold for transferring the paper web from the cylinder mold, and a drum roll about which the carrier passes, of a screen-faced extractor roll co-acting 33 with the drum roll and having pressure engagement with the drum roll through the carrier and web and directly engaging the web while at the under surface of the carrier without removal thereof from the carrier whereby to extract 40 water from the web and carrier prior to their passage from the drum roll.

2. In a cylinder paper machine, the combination with a cylinder vat unit including a vat, a cylinder mold rotating therein, a couch roll co-acting with the cylinder mold, a carrier passing between the couch roll and cylinder mold for transferring the paper web from the cylinder mold, and a drum roll about which the carrier passes, of a screen-faced extractor roll co-act- 45 ing with the drum roll and having pressure engagement with the drum roll through the carrier and web and directly engaging the web while at the under surface of the carrier without removal thereof from the carrier whereby to extract 52 water from the web and carrier prior to their passage from the drum roll, said drum roll comprising a perforated shell having an interiorly disposed suction box.

3. In a cylinder paper machine, the combina- 60 tion with a plurality of cylinder vat units, each including a vat, a cylinder mold rotating therein and a couch roll, a carrier passing between the couch roll and cylinder mold of each unit for transferring the paper web from the cylinder 65 molds and a drum roll about which the carrier passes, of a screen-faced extractor roll co-acting with the drum roll and having pressure engagement therewith through said carrier and web while directly contacting the web, auxiliary couch 70 rolls disposed between adjacent vats and screen-faced extractor rolls co-acting with said auxiliary couch rolls while directly contacting the web.

4. In a cylinder paper machine, the combina- 75 tion with a plurality of cylinder vat units, each

including a vat, a cylinder mold rotating therein and a couch roll, a carrier passing between the couch roll and cylinder mold of each unit for transferring the paper web from the cylinder molds and a drum roll about which the carrier passes, of a screen-faced extractor roll co-acting with the drum roll and having pressure engagement therewith through said carrier and web while directly contacting the web, auxiliary couch rolls disposed between adjacent vats and screen-faced extractor rolls co-acting with said auxiliary couch rolls while directly contacting the web, said drum roll comprising a perforated rotating shell having an interiorly disposed suction box.

5 5. In a cylinder paper machine, the combination with a plurality of cylinder vat units, each including a vat, a cylinder mold rotating therein and a couch roll, a carrier passing between the couch roll and cylinder mold of each unit for transferring the paper web from the cylinder molds and a drum roll about which the carrier passes, of a screen-faced extractor roll co-acting with the drum roll and having pressure engagement therewith through said carrier and web while directly contacting the web, auxiliary couch rolls disposed between adjacent vats and screen-faced extractor rolls coacting with said auxiliary couch rolls while directly contacting the web, said auxiliary couch rolls comprising perforated shells having interiorly disposed suction boxes.

10 6. In a cylinder paper machine, the combination with a plurality of cylinder vat units, each including a vat, a cylinder mold rotating therein and a couch roll, a carrier passing between the couch roll and cylinder mold of each unit for transferring the paper web from the cylinder molds and a drum roll about which the carrier passes, of a screen-faced extractor roll co-acting with the drum roll and having pressure engagement therewith through said carrier and web while directly contacting the web, auxiliary couch rolls disposed between adjacent vats and screen-faced extractor rolls co-acting with said auxiliary couch rolls while directly contacting the web, said drum roll and auxiliary couch rolls comprising perforated shells having interiorly disposed suction boxes.

15 7. In a cylinder paper machine, the combination with a plurality of cylinder vat units, each including a vat, a cylinder mold rotating therein and a couch roll, a carrier passing between the couch roll and cylinder mold of each unit for transferring the paper web from the cylinder molds and a drum roll about which the carrier passes, of a screen-faced extractor roll co-acting with the drum roll and having pressure engagement therewith through said carrier and web while directly contacting the web, auxiliary couch rolls disposed between adjacent vats, screen-faced extractor rolls co-acting with said auxiliary couch rolls while directly contacting the web and means associated with each extractor roll for drying the roll before its contact with the web.

20 8. In a cylinder paper machine, the combination with a cylinder vat unit including a vat, a cylinder mold rotating therein, a couch roll co-acting with the cylinder mold, a carrier passing between the couch roll and cylinder mold for transferring the paper web from the cylinder mold, and a pair of pressure-engaged rolls between which the carrier with the attached web has unaccompanied passage, without removal of the web from the carrier, acting to extract water from the felt and web immediately after their passage from the cylinder mold, the lower-

most of said rolls being screen-faced and engaging the web while at the under surface of the carrier.

9. The method of forming a pulp sheet consisting in collecting a saturated pulp web upon a felt, subjecting the felt and web to pressure with the web in contact with an underlying screen surface to dry the web to an extent preventing crushing by press pressures and then pressing the same.

5 10 10. Apparatus for forming a pulp sheet comprising a carrier felt, means for collecting a paper web thereon, a press through which the carrier passes and a plurality of extractor presses arranged between said web-forming means and the first-named press and through which the carrier with the web thereon passes, each of said extractor presses comprising a roll underlying the web and having a screen face, the web being in contact with said screen face.

15 20 11. In a cylinder paper machine, the combination with cylinder molds and a felt to receive a paper web from the cylinder molds, a plurality of extractor presses between the rolls of which the felt directly passes after leaving the cylinder molds, said extractor presses each comprising a screen-faced roll underlying the web and with which the web directly engages and a main press to which the felt and web carried thereby directly pass upon leaving the extractor presses.

25 30 12. In a cylinder paper machine, the combination with cylinder molds and a felt to receive a paper web from the cylinder molds, a plurality of extractor presses between the rolls of which the felt directly passes after leaving the cylinder molds, said extractor presses each comprising a screen-faced roll underlying the web and with which the web directly engages and a main press to which the felt and web carried thereby directly pass upon leaving the extractor presses, the felt-engaging roll of said main press comprising a suction roll.

35 40 45 50 13. The method of operating a cylinder paper machine including the usual pick-up felt and main press section comprising compressing the pick-up felt and the web carried thereby immediately upon passage of the felt from the cylinder molds while maintaining the paper web in contact with an underlying screen surface and then passing the web directly to said main press section.

55 60 14. The method of operating a cylinder paper machine consisting in collecting a paper web on a felt carrier, subjecting the web to a water-extracting operation, thereby fitting the web for pressing while protecting the affected fibres of the web by associating the web with a directly contacting screen support during such operation and subjecting the web while still on the carrier to the action of a suction roll.

65 70 75 15. The process of making paper which comprises forming a fibrous web on the conventional cylinder mold, picking up said web on a carrier felt on the under side thereof, directly contacting said fibrous web while on the felt with a bare screen surface, extracting water from the web while in contact with said screen surface, allowing said web to follow the carrier felt in its travel back over the machine, extracting further quantities of water from said web while still on said carrier felt by means of a suction press roll, removing said web from said carrier felt and directing said carrier felt back to the cylinder mold.

80 85 90 95 16. In the process of removing water from a

- fibrous web built up on the carrier felt in a cylinder type of paper machine, the step which comprises contacting said web and carrier felt directly against a bare screen surface with the web in direct engagement with said screen surface, extracting water from the web while in contact with said screen surface and allowing the web to follow the carrier felt back over the machine.
- 10 17. Apparatus for making paper, comprising means for collecting pulp upon a screen surface, a felt engaging said screen surface to remove the pulp therefrom and means acting upon the felt and pulp to extract water therefrom comprising a supporting screen surface directly contacting the pulp.
- 15 18. Apparatus for making paper comprising means for collecting pulp upon a screen surface, a felt engaging the pulp to remove it from said surface, a press acting upon the felt and pulp immediately following removal of the pulp from said screen, said press including a screen surface directly engaging the pulp during the operation of the press to thereby prevent dislocation of the fibres during the pressing operation.
- 20 19. Apparatus for making paper, comprising means for collecting pulp upon a screen surface, a felt engaging said screen surface to remove the pulp therefrom and means acting upon the felt and pulp to extract water therefrom comprising a supporting screen surface directly contacting the pulp, while the pulp is at the under surface of the carrier felt.
- 25 20. The process of making paper which comprises forming a fibrous web on the conventional cylinder mold, picking up said web on a carrier felt on the under side thereof, directly contacting said fibrous web while on the felt with a bare screen surface, extracting water from the web while in contact with said screen surface, extracting further quantities of water from said web while still on said carrier felt by means of a suction press roll, removing said web from said carrier felt and directing said carrier felt back to the cylinder mold.
- 26 21. In a cylinder paper machine, the combination of a vat unit having a cylinder mold therein and a co-acting couch roll, a pick-up felt passing between the cylinder mold and couch roll for collecting a paper web on the under surface thereof, a drum roll spaced approximately horizontally from the vat unit, said pick-up felt extending approximately horizontally from the vat unit to said drum roll with the paper web on the under side thereof, and a screen faced extractor roll co-acting with the drum roll and directly engaging the web on the under surface of the pick-up felt.
- 27 22. Apparatus as claimed in claim 17 wherein the means acting upon the felt and pulp further includes a suction roll.
- 28 23. Apparatus as claimed in claim 17 wherein the means acting upon the felt and pulp further includes a suction roll acting through the felt.
- 29 24. Apparatus as claimed in claim 18 wherein the means acting upon the felt and pulp further includes a suction roll.
- 30 25. Apparatus as claimed in claim 18 wherein the means acting upon the felt and pulp further includes a suction roll acting through the felt.
- 31 26. Apparatus as claimed in claim 19 wherein the means acting upon the felt and pulp further includes a suction roll.
- 32 27. Apparatus as claimed in claim 19 wherein the means acting upon the felt and pulp further includes a suction roll acting through the felt.

WM. H. SUTHERLAND.
CHARLES L. ELLIS.
